US00D368252S

United States Patent [19]

Nakai

[11] Patent Number: Des. 368,252

[45] Date of Patent: **Mar. 26, 1996

[54] PROGRAMMABLE LOGIC CONTROLLER

[75] Inventor: **Tatsunobu Nakai**, Osaka, Japan[73] Assignee: **Idec Izumi Corporation**, Osaka, Japan

[**] Term: 14 Years

[21] Appl. No.: 20,581

[22] Filed: Mar. 29, 1994

[30] Foreign Application Priority Data

Oct. 4, 1993 [JP] Japan 5-30187

CLAIM

The ornamental design for a programmable logic controller, as shown and described.

DESCRIPTION

FIG. 1 is a front elevational view of a programmable logic controller showing my new design;
FIG. 2 is a rear elevational view thereof;
FIG. 3 is a top plan view thereof;
FIG. 4 is a bottom plan view thereof;
FIG. 5 is a left side elevational view thereof;
FIG. 6 is a right side elevational view thereof;
FIG. 7 is a front, left and bottom perspective view thereof; and,
FIG. 8 is a perspective view thereof as seen from the rear and upper right.
